LIGHTER

Henry T. Schiff, Chicago, Ill.

Application May 27, 1933. Serial No. 673,180

12 Claims. (Cl. 67—4.1)

This invention relates to improvements in lighters of the pyrophoric or ferro-cerium type, in which the sparks are produced by the rapid friction of steel against cerium iron or similar alloys.

In lighters of this character there is usually provided a disc or wheel against which the ferro-cerium is forced by a spring and the wheel is provided with a toothed or serrated periphery to produce the spark, and also providing a surface to be engaged by the finger of the operator for rotating the wheel.

It is one of the objects of the present invention to produce an improved lighter of this character in which the wheel and the spring element are dispensed with, and to provide an improved lighter in which the steel element is in the nature of a match or element carrying a wick or material which absorbs or holds the fuel fluid, and which element is insertable into and removable from the lighter, the end of which is adapted to be drawn across the cerium iron to produce the spark to cause the flame which is sustained by the fuel soaked wick or material. The body of the lighter contains an absorbent material against which the wick or flame sustaining material on the match or removable element is adapted to contact so as to be saturated with the fuel to be ignited when the element is again drawn across the cerium iron.

A further object is to provide an improved construction of match or element of a sectional construction, the active end of which is held against rotation while the body portion of the element is advanced or secured in position in the lighter or withdrawn therefrom so as to prevent injury or the withdrawing of the absorbent material within the lighter body, by the insertion or removal of the match element.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention and in which

Figure 1 is an elevation of a device of this character constructed in accordance with the principles of this invention.

Figure 2 is a right hand end elevation of Figure 1.

Figure 3 is a view partly in section and partly in elevation as taken on line 3—3, Figure 2, and on an enlarged scale.

Figure 4 is a longitudinal sectional view of the match or flame sustaining element.

Figure 5 is a top plan view of Figure 4 on an enlarged scale.

Figure 6 is a detail sectional view taken on line 6—6 Figure 3.

Figure 7 is a horizontal sectional view taken on line 7—7, Figure 3.

Figure 8 is a detail perspective view of the 65 filling or absorbent material within the lighter body.

Figure 9 is a view partly in side elevation and partly in section of another form of the invention.

Figure 10 is a detail sectional view taken on 70 line 10—10, Figure 9.

Referring more particularly to the drawings and to the form of the invention shown in Figures 1 to 8, the numeral 10 designates generally a body portion of any desired size and configuration provided on one side with an open groove 12 in which is arranged a strip of ferro-cerium iron 13 secured in position in any desired or suitable manner.

The body is closed and one of the end walls 80 is provided with an opening having a cast portion 14 therearound to form a wall 15 of substantial thickness so that threads 16 may be provided therein to encompass the opening in the wall of the body.

Arranged within the body is a pad 17 constructed of any suitable absorbent material, such as felt, cotton or the like, and this pad is of a general configuration to conform to and fit within the body 10 to substantially fill the body. In 90 one edge of the pad is a cut away portion 18 preferably of triangular configuration and into which portion 18 the casting 14 extends so that the cut away portion 18 will be in alignment and register with the opening in the end wall of 95 the body 10.

The numeral 19 designates a bar or member of any desired size and configuration and constructed of any suitable material, preferably tubular for the sake of lightness. Within one end of 100 the member 19 is inserted one end of a solid member 20 being held in position in any suitable manner, and this member 20 is provided with a circumferential flange 21 of a diameter considerably greater than the external diameter of the member 19. The upper extremity of the member 20 is preferably reduced as at 22, and the member is provided with an open circumferential groove 23 extending therearound.

An element 24 preferably constructed of steel, 110 is inserted into an opening 25 in the end of the element 20 and the free extremity of the element 24 is preferably tapered as at 26 and is provided with a head 27 of a diameter appreciably greater than the external diameter of the portion of the 115 tapered end of the element 24 which is in proximity to the member 20 so as to provide the circumferentially projecting flange encompassing the member.

A sleeve 28 encompasses the end of the mem- 120

- ber 20 as well as the element 24 and terminates a distance considerably short of the extremity 27 of the element 24. The internal diameter of the sleeve 28 is considerably greater than the 5 external diameter of the element 24 and encompassing the element 24 and filling the sleeve 28 and the element 24 is an absorbent material such as asbestos or any other suitable material which absorbs fuel and will operate to sustain a flame 10 at the end of the sleeve 28 when the fuel is ignited.
- The free extremity of the sleeve 28 preferably terminates short of the free extremity of the element 29 so as to provide a portion 30 beyond the end of the sleeve 28 for supporting combustion. The sleeve 28 is held in position so as to rotate with respect to the member 20 in any desired or suitable manner, such as by deflecting a portion 31 of the sleeve 28 into the recess 20 23. The free end of the sleeve 28 is preferably provided with spaced fingers or portions 32 which are adapted to be slightly deflected so as to hold the element 30 against accidental displacement with respect to the element 24 and the sleeve 25 28. The member 20 is provided with external threads 33.

With this construction it will be manifest that the sleeve 28 is adapted to rotate freely with respect to the member 20, so that in use when the 30 extremity of the element 24 and the sleeve 28 is inserted into the body 10 of the lighter through the opening in the end wall, the threads 33 will engage the threads 16 in such opening and the element 19 will be connected to the body 10. 35 By rotating the element 19 with respect to the body 10 the threads 16 will feed the end of the element into the opening 18 in the pad or the filler material 17, and when the walls of the opening 18 contact with any portion of the sleeve 40 28, the sleeve will be held against rotation while the body of the element 19 may be rotated, thereby insuring the non-rotation of the sleeve 28, so that the sleeve 28 and the element 24 may be advanced by the member 19 while the 45 latter is rotated and while the sleeve 28 and member 26 are held against rotation. The sleeve 28 will be advanced sufficiently so as to cause the extremity of the material 30 to contact with the walls of the opening 18 so that the material 50 30 will be kept moist with the fuel fluid from the pad or filler 17. This construction also insures that the material 17 will not be injured by the rotation of the element 24 of the sleeve 28, and likewise no part of the material 17 will 55 be withdrawn when the element 19 is detached from the body portion 10.

Any suitable means, such as a loop or eye 34 may be connected to the body of the lighter and to which loop or eye is connected a chain or 60 suspension device 35, by means of which the device may be hung from any suitable support.

In the form of the invention shown in Figure 9, the element 19 is dispensed with, and in lieu thereof there is provided a handle 36 preferably provided with a milled circumference 37 in the form of a knob or button, which adapts the device to be more readily carried in the pocket.

In this form of the invention there is also shown a means whereby the device may be 70 movably mounted upon a support 38 such as a window or the like, and there is provided a cup shaped member 39 secured by means of a fastening device 40 to the body portion 10. A cap 41 provided with radially arranged fingers 42 may be secured in position, preferably by means of the

same fastening device 40, and these fingers serve as a means for protecting the cup 39 and to facilitate in the fastening of the cup 39 to the support 38.

In use and when the light sustaining element 19 is removed from the body by unscrewing the same, the fuel sustaining element 30 will contain a sufficient amount of fuel by reason of its being held in contact with the body or material 18 when inserted in the body portion to support combustion, when the extremity 27 of the element 26 is rapidly drawn across the cerium iron 13. The flame may be extinguished when desired, in any suitable manner, and the end of the flame supporting element again inserted into the body so that there will be a sufficient supply of fuel to again support a flame when a spark is produced by friction between the spark producing elements.

While the preferred forms of the invention have been herein shown and described, it is to be understood that various changes may be made in the details of construction and in the combination and arrangement of the several parts, within the scope of the claims, without departing from the spirit of this invention.

What is claimed as new is:—

1. A lighter of the character described comprising a fuel reservoir, a pad within the reservoir, there being an opening through one wall of the reservoir, a sectional spark producing element, one of which is freely rotatable axially with respect to the other, one of said sections serving as a handle, one end of said element being insertable into the reservoir through said opening, and means for effecting a securing of the element against removal from the reservoir, one of said sections being held in contact with said pad and held against rotation thereby while the other section is being rotated to effect a securing and a disconnecting of the element with respect to the reservoir.

2. A lighter of the character described comprising a fuel reservoir, a pad within the reservoir, there being an opening through one wall of the reservoir, a sectional spark producing element, one of which is freely rotatable axially with respect to the other, one of said sections serving as a handle, one end of said element being insertable into the reservoir through said opening, and means for effecting a securing of the element against removal from the reservoir, a wick carried by the end of one section, said wick being held in contact with said pad and held with the section supporting the same, against rotation while the other section is being rotated to effect a securing and disconnecting of the element with respect to the reservoir.

3. A lighter of the character described embodying a spark producing element comprising two sections arranged end to end and axially 135 rotatable one with respect to the other, a wick carried adjacent the end of one of said sections, a closed reservoir having an opening through one wall, a fuel absorbing pad in the reservoir and against which pad the wick is adapted to be 140 held when one end of one of the sections is inserted into the reservoir through said opening, and interengaging means between the other section and the wall of said opening for securing the element to the reservoir, the first said section 145 being held against rotation by the pad while the other section is being rotated to effect a securing of the element to the reservoir and a separation therefrom and while the first said section is being longitudinally moved.

4. A lighter of the character described embodying a spark producing element comprising two sections arranged end to end and axially rotatable one with respect to the other, a wick carried adjacent the end of one of said sections, a closed reservoir having an opening through one wall, a fuel absorbing pad in the reservoir and against which pad the wick is adapted to be held when one end of one of the sections is inserted into the reservoir through said opening, and interengaging means between the other section and the wall of said opening for securing the element to the reservoir, the first said section being held against rotation by the pad while the other section is being rotated to effect a securing of the element to the reservoir and a separation therefrom and while the first said section is being longitudinally moved, the extremity of said element projecting beyond the wick for a substantial distance, said extremity being shaped to form a comparatively narrow and laterally projecting circumferential flange. 80
5. A lighter of the character described embodying a fuel reservoir, an absorbent pad therein, a spark producing element projectable into the reservoir to cause one end thereof to contact with the pad, and means for securing the element to the reservoir by an axial rotation of the element, the said pad maintaining against rotation, the end of the said element which contacts with the pad, during the said axial rotation of the element. 85
6. A lighter of the character described embodying a fuel reservoir, an absorbent pad therein, a spark producing element, a wick carried adjacent one end of the element, said element and wick being insertable into the reservoir to cause the wick to contact with the pad, and means for securing the element to the reservoir by an axial rotation of the element, the said pad maintaining the wick and the adjacent end of the element against rotation, during the axial rotation of the said element. 90
7. A lighter of the character described embodying a fuel reservoir, an absorbent pad therein, a spark producing element projectable into the reservoir to cause one end thereof to contact with the pad, means for securing the element to the reservoir by an axial rotation of the element, the said pad maintaining against rotation, the end of the said element which contacts with the pad, during the said axial rotation of the element, and a second spark producing element carried by the outside of the reservoir and with which second element the first said element is adapted to co-operate to frictionally produce a spark. 95
8. A lighter of the character described embodying a fuel reservoir, an absorbent pad therein, a spark producing element, a wick carried adjacent one end of the element, said element and wick being insertable into the reservoir to cause the wick to contact with the pad, means for securing the element to the reservoir by an axial rotation of the element, the said pad maintaining the wick and the adjacent end of the element against rotation, during the axial rotation of the said element, and a second spark producing element carried by the outside of the reservoir and with which second element the first said element is adapted to co-operate to frictionally produce a spark. 100
9. A lighter of the character described embodying a fuel reservoir, an absorbent pad therein, a spark producing element projectable into the reservoir to cause one end thereof to contact with the pad, means for securing the element to the reservoir by an axial rotation of the element, the said pad maintaining against rotation, the end of the said element which contacts with the pad, during the said axial rotation of the element, and means for securing the said reservoir to a support. 105
10. A device of the character described embodying a lighter element comprising two sections connected together for relative axial rotation, a spark producing element connected to and projecting beyond the end of one of said sections, a wick carried by the other of said sections, a reservoir having an opening through one wall and through which opening the first said section is insertable into the reservoir, interengaging threads between the other of said sections and the wall of said opening for securing the said element to the reservoir, and a pad in the reservoir adapted to be engaged by said wick and the adjacent end of the wick supporting section, said pad serving to frictionally hold the wick and said element against rotation while they are being longitudinally moved by the rotation of said other section. 110
11. A device of the character described embodying a lighter element comprising two sections connected together for relative axial rotation, a spark producing element connected to and projecting beyond the end of one of said sections, a wick carried by the other of said sections, a reservoir having an opening through one wall and through which opening the first said section is insertable into the reservoir, interengaging threads between the other of said sections and the wall of said opening for securing the said element to the reservoir, a pad in the reservoir adapted to be engaged by said wick and the adjacent end of the wick supporting section, said pad serving to frictionally hold the wick and said element against rotation while they are being longitudinally moved by the rotation of said other section, and a second spark producing element with which the first recited spark producing element is adapted to co-operate to frictionally produce a spark. 115
12. A device of the character described embodying a lighter element comprising two sections connected together for relative axial rotation, a spark producing element connected to and projecting beyond the end of one of said sections, a wick carried by the other of said sections, a reservoir having an opening through one wall and through which opening the first said section is insertable into the reservoir, interengaging threads between the other of said sections and the wall of said opening for securing the said element to the reservoir, a pad in the reservoir adapted to be engaged by said wick and the adjacent end of the wick supporting section, said pad serving to frictionally hold the wick and said element against rotation while they are being longitudinally moved by the rotation of said other section, and means for supporting said reservoir. 120
13. A device of the character described embodying a lighter element comprising two sections connected together for relative axial rotation, a spark producing element connected to and projecting beyond the end of one of said sections, a wick carried by the other of said sections, a reservoir having an opening through one wall and through which opening the first said section is insertable into the reservoir, interengaging threads between the other of said sections and the wall of said opening for securing the said element to the reservoir, a pad in the reservoir adapted to be engaged by said wick and the adjacent end of the wick supporting section, said pad serving to frictionally hold the wick and said element against rotation while they are being longitudinally moved by the rotation of said other section, and means for supporting said reservoir. 125
14. A device of the character described embodying a lighter element comprising two sections connected together for relative axial rotation, a spark producing element connected to and projecting beyond the end of one of said sections, a wick carried by the other of said sections, a reservoir having an opening through one wall and through which opening the first said section is insertable into the reservoir, interengaging threads between the other of said sections and the wall of said opening for securing the said element to the reservoir, a pad in the reservoir adapted to be engaged by said wick and the adjacent end of the wick supporting section, said pad serving to frictionally hold the wick and said element against rotation while they are being longitudinally moved by the rotation of said other section, and means for supporting said reservoir. 130
15. A device of the character described embodying a lighter element comprising two sections connected together for relative axial rotation, a spark producing element connected to and projecting beyond the end of one of said sections, a wick carried by the other of said sections, a reservoir having an opening through one wall and through which opening the first said section is insertable into the reservoir, interengaging threads between the other of said sections and the wall of said opening for securing the said element to the reservoir, a pad in the reservoir adapted to be engaged by said wick and the adjacent end of the wick supporting section, said pad serving to frictionally hold the wick and said element against rotation while they are being longitudinally moved by the rotation of said other section, and means for supporting said reservoir. 135
16. A device of the character described embodying a lighter element comprising two sections connected together for relative axial rotation, a spark producing element connected to and projecting beyond the end of one of said sections, a wick carried by the other of said sections, a reservoir having an opening through one wall and through which opening the first said section is insertable into the reservoir, interengaging threads between the other of said sections and the wall of said opening for securing the said element to the reservoir, a pad in the reservoir adapted to be engaged by said wick and the adjacent end of the wick supporting section, said pad serving to frictionally hold the wick and said element against rotation while they are being longitudinally moved by the rotation of said other section, and means for supporting said reservoir. 140
17. A device of the character described embodying a lighter element comprising two sections connected together for relative axial rotation, a spark producing element connected to and projecting beyond the end of one of said sections, a wick carried by the other of said sections, a reservoir having an opening through one wall and through which opening the first said section is insertable into the reservoir, interengaging threads between the other of said sections and the wall of said opening for securing the said element to the reservoir, a pad in the reservoir adapted to be engaged by said wick and the adjacent end of the wick supporting section, said pad serving to frictionally hold the wick and said element against rotation while they are being longitudinally moved by the rotation of said other section, and means for supporting said reservoir. 145
